(21) Appl. No.: **29/319,144**

The ornamental design for a knife sheath, as shown and described.

(22) Filed: **Jun. 4, 2008**

DESCRIPTION

(51) **LOC (9) Cl.** 03-01

FIG. 1 is a perspective view of a knife sheath in accordance with the present invention;

(52) **U.S. Cl.** D3/220

FIG. 2 is a side view of the knife sheath seen in FIG. 1;

(58) **Field of Classification Search** D3/220;

FIG. 3 is a top view of the knife sheath seen in FIG. 1;

D22/118, 117; 224/232; 30/143, 146, 151–153;

D8/95–99; D7/637–641

FIG. 4 is an end view of the knife sheath seen in FIG. 1;

See application file for complete search history.

FIG. 5 is a perspective view of a second embodiment of a knife sheath in accordance with the present invention;

(56) **References Cited**

FIG. 6 is a side view of the second embodiment of the knife sheath seen in FIG. 5;
